UNITED STATES PATENT OFFICE.

BOYD E. MARTZ, OF WILLIAMSBURG, PENNSYLVANIA.

SPECTACLE-CASE CLIP.

1,330,208.

Specification of Letters Patent. Patented Feb. 10, 1920.

Application filed April 26, 1918. Serial No. 230,930.

To all whom it may concern:

Be it known that I, BOYD E. MARTZ, a citizen of the United States, residing at Williamsburg, in the county of Blair and State 5 of Pennsylvania, have invented certain new and useful Improvements in Spectacle-Case Clips; and I do hereby declare the following to be a full, clear, and exact description of the invention, such as will enable others 10 skilled in the art to which it appertains to make and use the same.

This invention relates to improvements in spectacle or eye-glass case clips and has for one of its objects the provision of a device 15 of this character which can be readily and conveniently applied to an ordinary case for the purpose of firmly securing the same in the pocket of the user or to any portion of the garment.

Another object of this invention is the provision of a resilient member having formed upon one end a resilient grip adapted to grip a portion of the case and have its free end curved to form a clip adapted to 20 engage over a portion of the garment to confine the same between itself and the case thereby firmly securing the case to the garment.

A further object of this invention is the 30 provision of a clip of the above stated character, which shall be simple, durable and efficient, and which may be manufactured and sold at a comparatively low cost.

With these and other objects in view as 35 will become more apparent as the description proceeds, the invention consists in certain novel features of construction, combination, and arrangement of parts as will be hereinafter fully described and claimed.

For a complete understanding of my 40 invention, reference is to be had to the following description and accompanying drawing, in which:

Figure 1 is a vertical sectional view of a 45 spectacle or eye-glass case having a clip applied thereto constructed in accordance with my invention.

Fig. 2 is a perspective view of the clip.

Referring in detail to the drawing, the 50 numeral 1 indicates as an entirety a spectacle or eye-glass case consisting of the usual body portion 2 having the hinged lid 3 to which my invention is adapted to be applied. The clip 4 is constructed from a

single length of resilient material 5 which 55 is tapered toward one end. The enlarged end of the member 5 is bent upon itself to form a clasp 6 adapted to engage one edge of the cover 3 and firmly grip the same as clearly illustrated in Fig. 1. The member 5 60 is offset outwardly and downwardly as illustrated at 7 and has its free reduced end 8 rolled upon itself as illustrated at 9 to form a gripping tongue, which gripping tongue is adapted to grip a portion of a garment 10 65 between the same and the lid 3 of the case 1, thereby firmly securing the case to the garment. By having the free end of the tongue rolled as illustrated at 9 it will, when applied to the garment, bite into the garment 70 offsetting the same as illustrated at 11 preventing the garment from slipping from under the tongue.

From the foregoing description taken in connection with the accompanying drawing, 75 it will be noted that a novel form of clip has been provided, which can be readily and conveniently applied to various types of eye-glass or spectacle cases and which will firmly hold itself upon the case and firmly 80 secure the case to a garment.

While I have shown and described the preferred embodiment of my invention, it will be understood that minor changes in construction, combination and arrangement 85 of parts may be made without departing from the spirit and scope of the invention as claimed.

Having thus described my invention, what 90 I claim as new is:

A clip comprising a member constructed from a single length of resilient material tapered toward one of its ends, the enlarged end of said member bent upon itself to engage both faces of the wall of the receptacle, said member from its enlarged portion being offset outwardly and having its free end rolled to form a spring gripping tongue adapted to grip a garment between itself and the receptacle, the rolled end of 95 said tongue biting into the garment to prevent the tongue from disengaging the same.

In testimony whereof I affix my signature in presence of two witnesses.

BOYD E. MARTZ.
